[57] **CLAIM**

The ornamental design for a combined slider and key pad input device for a computer, as shown and described.

DESCRIPTION

FIG. 1 is a top end and side perspective view of a combined slider and key pad input device for a computer showing our new design with the key pad being moved to expose a portion of the slider;

FIG. 2 is a top opposite end and side perspective view thereof;

FIG. 3 is a top end and side perspective view thereof with the slider and key pad in a fully closed position;

FIG. 4 is an opposite side elevation view thereof of FIG. 1;

FIG. 5 is an opposite side elevation thereof of FIG. 3;

FIG. 6 is an opposite side elevation thereof of FIG. 2;

FIG. 7 is a top plan view thereof of FIG. 2;

FIG. 8 is a side elevation view thereof of FIG. 2;

FIG. 9 is a bottom plan view thereof of FIG. 2;

FIG. 10 is a top plan view thereof of FIG. 1;

FIG. 11 is a side elevation view thereof of FIG. 1;

FIG. 12 is a bottom plan view thereof of FIG. 1;

FIG. 13 is a top plan view thereof of FIG. 3;

FIG. 14 is a side elevation view thereof of FIG. 3;

FIG. 15 is a bottom plan view thereof of FIG. 3;

FIG. 16 is a top perspective view of the key pad shown separately for clarity of illustration only; and,

FIG. 17 is a perspective view of the slider shown separately for clarity of illustration only.
